UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 21, 1918. Serial No. 255,114.

To all whom it may concern:

Be it known that I, ALBEN E. LUNDELL, a citizen of the United States, residing at New York, in the county of Bronx, State of New York, have invented certain new and useful Improvements in Telephone-Exchange Systems, of which the following is a full, clear, concise, and exact description.

This invention relates to telephone exchange systems, and particularly to an improved arrangement for controlling the operation of selectively operable switching devices employed in machine switching telephone exchange systems.

15 It is the object of the present invention to provide an arrangement whereby, in response to the adjustment of a controlling apparatus, the setting of a selectively operable switching device may be effaced, preferably by restoring the switching device to normal.

With this object in view, according to one feature of the present invention the restoring means, such as the restoring magnet or a device controlling the operation of the restoring magnet, of a selectively operable switching device may be actuated under the control of the apparatus, the adjustment of which determines the operation of the switching device. Due to the provision of this arrangement, an operator or subscriber controlling by means of an apparatus, such as a substation or central office sending device, the setting of a selector switch, may, by operating the sending device, cause the restoration of the selector if the sending device has been erroneously operated.

According to another feature of the invention, a selectively operable switching device may be restored in response to a selection controlling operation of the controlling apparatus, whereby if, e. g., a semi-automatic operator notices that she depressed a wrong key on her sender controlling keyboard, she will simply have to depress the correct key, whereupon the selector switch, operated in accordance with the designation of the wrong key, is restored and is again caused to operate but in accordance with the designation of the correct key.

50 These and other features of the invention will be more readily understood from the following description of a preferred embodiment of the invention and the appended claims.

In the drawings, Fig. 1 represents a semi-automatic telephone operator's cord circuit terminating in a selectively operable switching device; Fig. 2 (to be placed below Fig. 1) represents the operator's sending and controlling apparatus, and Fig. 3 (to be placed to the right of Fig. 1) represents a second selectively operable switching device.

Only so much of the circuits and apparatus of a semi-automatic telephone exchange is disclosed in the drawings as is necessary for a clear understanding of the present invention. The selector switches are preferably of the same type as the one disclosed in Patent No. 1,123,696 to E. B. Craft and J. N. Reynolds, and the sequence switches of the structure disclosed in Patent No. 1,127,808 to J. N. Reynolds and C. F. Baldwin. For the sake of simplicity the selectors are shown as provided with only one set of wipers instead of five sets as disclosed in the patent, and for this reason the tripping mechanism of the patent has also been left out. All the sequence switch cams shown in a figure are controlled by the sequence switch illustrated in that figure. The showing of the sequence switch cams is diagrammatic and not in accordance with their structural relation to the sequence switch power magnets. In practice, the operator's sending and controlling equipment is not permanently associated with a cord circuit, but is selectively and automatically associated with a cord circuit taken for use by means of a cord finder. A complete disclosure of the circuits of the operator's sending and controlling apparatus and the selector switches may be had from Patent No. 1,168,319 to A. E. Lundell. However, it will obviously appear to those skilled in the art that this invention may be practiced in systems employing circuits and apparatus of a widely varying character.

A calling subscriber at station 100 desiring to initiate a call removes his receiver from the switchhook whereupon a line relay 101 becomes energized, and by causing the lighting of a calling lamp 102 signals the operator of the presence of a call at her board. The operator thereupon inserts the answering plug 103 of one of her cords into the answering jack 104 in which the calling line terminates. A circuit is closed there-

upon through the sleeve contacts of the jack 104 and plug 103, and the windings of relays 105 and 106 for energizing these two relays. The cutoff relay 105 by energizing 5 causes the deenergization of line relay 101 whereupon the lamp 102 is extinguished. The relay 106 closes a circuit from ground, through its armature and front contact, the upper left-hand contact of sequence switch 10 10 cam 107 and the power magnet of sequence switch 108 to grounded battery. The sequence switch is moved out of position 1 and under the control of its normal contact 109 into position 2. A circuit is now closed 15 from ground, through the lower contact of sequence switch cam 110, conductor 111, the upper contact of sequence switch cam 200 and the winding of a relay 201, to grounded battery. Relay 201 becomes energized and 20 closes a circuit from ground, through its left-hand armature and front contact, the upper right-hand contact of sequence switch cam 202, and the power magnet of a sequence switch 203, to grounded battery. The 25 sequence switch is moved out of position 1 and under the control of its normal contact 204, into position 4. The relay 201 does not become deenergized when the sequence switch 203 moves out of position 1, because 30 a locking circuit is closed for this relay in positions 1 to 16 of the sequence switch 203, from grounded battery, through the winding of this relay, the lower contact of sequence switch cam 200, the right-hand contact and armature of relay 201, conductor 205, and the upper contact of sequence switch cam 110, to ground.

In the meantime the operator has conversed with the calling subscriber by connecting her telephone head set 112 by means of listening key 113 or other well-known device to the connecting circuit taken for use. Having learned the number of the desired subscriber's line, the operator adjusts her controlling equipment by depressing actuating members, such as keys, representing the digits of the called number. In the present case it will be assumed that she depresses keys 206 and 207. The operator 40 depresses also her start key 208, which will cause the sending out of the impulses under the control of key 207 after the sending of the impulses under the control of key 206 has terminated. The keys in one row with key 206 adjust the sending apparatus to 45 control the operation of selector 122, and those in one row with key 207 adjust the apparatus to control the operation of selector 300 in accordance with the digits of 50 the called number.

In position 2 of sequence switch 108 and position 4 of sequence switch 203, a circuit is closed from grounded battery, through the winding of relay 114, the lower right-hand contact of cam 116, conductor 115, the

outer armature and back contact of the upper zero counting relay, the winding of a stepping relay 210, the upper contact of cam 209, conductor 211, and the lower contact of sequence switch cam 117, to ground. The relays 210 and 114 become energized. The relay 114 closes a locking circuit for itself through its left-hand contact and armature, and the lower left-hand contact of cam 116, and a circuit from ground 75 through its right-hand armature and front contact, the lower right-hand contact of sequence switch cam 118, and the power magnet of sequence switch 108, to grounded battery. The sequence switch 108 is moved out of position 2 and into position 3. A circuit is now closed from grounded battery, through the winding of a magnet 119, the left-hand contact of sequence switch cam 120, and the right-hand front contact and armature of relay 114, to ground. Magnet 119 becomes energized and by attracting its armature presses brush rod 121 of the selector 122 against an up-drive roller 123 constantly rotating in the direction indicated by the arrow. Wipers 124, 125 and 126 and commutator brushes 127 and 128 of the selector 122 carried by the brush rod are moved in an upward direction. The wipers 124 to 126 are arranged to engage 90 terminals of a bank 129 in which terminate called lines such as the trunk leading to selector 300. The commutator brushes 127 and 128 are arranged to engage the conducting and insulated portions of commutator segments 130 and 131, respectively.

Upon the actuation of the key 206, a circuit was closed from ground, through the front contact and left-hand armature of relay 201, contact of key 206, resistance 251, 105 and the winding of relay 250. Relay 250 is marginal in operation and does not become energized by current flowing in this circuit. In response to the energization of relay 210, a circuit is closed from ground, 110 through the armature and front contact of this relay, the upper contact of sequence switch cam 220, contact 221 of the key 206, and the winding of the lower counting relay 0, to grounded battery. This counting 115 relay becomes energized and closes a locking circuit for itself from ground, through the right-hand contact of sequence switch cam 222, the armature and front contact of the lower 0 counting relay, and the winding of the upper and lower 0 counting relays, to grounded battery. The upper 0 120 counting relay does not become energized upon the closure of this locking circuit, because of a shunt path closed to its winding 125 through the armature and front contact of relay 210, to ground. As soon as the commutator brush 127 engages for the first time the conducting portion of commutator segment 130, a shunt path is closed from 130

ground, through commutator brush 127, the commutator segment 130, conductor 132, the upper and the lower left-hand contacts of cam 116, and the left-hand armature and contact of relay 114, to the winding of this relay. Due to the closure of this shunt path the current flowing through the winding of the stepping relay 210 is not sufficient to maintain it energized, and this relay, by re-
tracting its armature, permits the energiza-
tion of the upper counting relay 0. The
upper counting relay 0 opens in its outer
back contact the above traced circuit of re-
lays 210 and 114. The relay 210 becomes
deenergized. The relay 114, however, is
maintained energized by current flowing
through the above traced path including
conductor 132 and the commutator brush
127, as long as this commutator brush is
in engagement with the conducting portion
of the segment 130.

As soon, however, as this commutator
brush engages the insulated portion of the
segment 130 (at which time the selector
switch wipers are centered on the selected
set of terminals), the relay 114 becomes de-
energized and by opening its right-hand
front contact the circuit of magnet 119
causes the arresting of the upward travel
of the wipers of selector 122. A circuit is
also closed from ground, through the right-
hand back contact and armature of relay
114, the left-hand contact of cam 118, and the
power magnet of sequence switch 108, to
grounded battery, for driving this switch
out of position 3 and into position 6. A
circuit is now closed from ground, through the
lower and the upper right-hand contacts
of sequence switch cam 135, and the right-
hand winding of relay 136, to grounded bat-
tery. The relay 136 becomes energized and
closes a circuit from ground, through its
right-hand armature and front contact, the
right-hand contact of sequence switch cam
137, and the power magnet of sequence
switch 108, to grounded battery, for driving
this sequence switch out of position 6 and
into position 7. If, at this time, the selector
122 is resting with its wipers on the ter-
minals of a busy trunk, that is to say, on ter-
minals the multiples of which are engaged
by the wipers of another selector, the test
terminal with which the wiper 124 contacts
is connected to ground in a manner to be
hereinafter set forth. For this reason upon
the energization of the relay 136, a locking
circuit is closed from grounded battery,
through the left-hand winding, front con-
tact and left-hand inner armature of relay
136, and the wiper 124 to ground at the
other selector. The relay 136 being ener-
gized, as soon as the sequence switch 108
reaches position 7 a circuit is closed from
ground, through the right-hand armature
and front contact of relay 136, the right-

hand contact of cam 120 and the winding of
magnet 119, to grounded battery. The mag-
net 119 again becomes energized and causes
the further travel of the selector switch
wipers in an upward direction. The selector
switch wipers will continue to travel until
the test wiper 124 encounters an idle test
terminal, that is to say, one to which no
ground is connected, whereupon the locking
circuit of the relay 136 is opened. In the
present case, it is assumed that such idle
trunk is the one designated by the numerals
140, 141 and 142. Upon the deenergization
of relay 136, the circuit of magnet 119 is
opened and a circuit is closed through the
right-hand armature and back contact of
relay 136, the left-hand contact of cam 137,
and the power magnet of sequence switch
108, to grounded battery, for moving this
sequence switch out of position 7 and into
position 11. The multiples of the contacts
in which trunk conductors 140, 141 and 142
terminate are guarded against seizure by
other selectors due to the connection of a
ground through the upper left-hand con-
tact of cam 117, the left-hand inner back
contact and armature of relay 136, and the
wiper 124. This ground is also extended
through conductor 140 and the winding of
a relay 301, to grounded battery, causing
the energization of this relay.

At the sender, the upper zero counting re-
lay closed a circuit from ground, through the
left-hand contact of cam 222, the inner ar-
mature and front contact of the upper zero
counting relay and the power magnet of se-
quence switch 203, to grounded battery, caus-
ing the movement of this sequence switch out
of position 4 and into position 5. From this
position the sequence switch is moved into
position 6, the driving circuit being closed
from grounded battery, through the power
magnet of the sequence switch, the lower con-
tact of cam 202, and the contact of the key
208. In positions 4 to 8 of the sequence
switch 203, a circuit is closed from grounded
battery, through a resistance 260, sequence
switch cam 261 and the lower winding of re-
lay 230 to ground. Current flowing through
this circuit polarizes the relay 230 in such a
manner that the relay will not attract its ar-
mature unless its upper winding is traversed
by current flowing in a certain direction.

As soon as the sequence switch 108 reaches
position 11, a circuit is closed from ground,
through the left-hand contact of sequence
switch cam 304, conductor 141, wiper 125, the
upper contact of sequence switch cam 144,
conductor 211, the lower contact of sequence
switch cam 209, the upper winding of a re-
lay 230 and a non-inductive resistance 262 in
parallel, the winding of relay 210, the outer
back contact and armature of the upper
counting relay 0, conductor 115, the lower
contact of cam 143, wiper 126, conductor 142,

the lower right-hand contact of sequence switch cam 303, and the winding of relay 302, to grounded battery. Relays 210 and 302 become energized. Relay 230, however, does not respond to current flowing in this direction through its upper winding. The non-inductive resistance 262 is provided so as to insure the proper operation of relay 210. Relay 302 closes a locking circuit for itself through its left-hand armature and front contact, and lower left-hand contact of sequence switch cam 303, and a circuit from ground, through its right-hand armature and front contact, the lower left-hand contact of sequence switch cam 305, and the power magnet of sequence switch 306 to grounded battery. The sequence switch is moved out of position 1 and under the control of its normal contact 307, is moved to position 2. In this position of the sequence switch, a circuit is closed from ground, through the right-hand armature and front contact of relay 302, the lower contact of sequence switch cam 308, and the winding of a magnet 309, to grounded battery. Magnet 309 by attracting its armature, presses brush rod 310 of the selector 300 against a roller 311 constantly rotating in the direction indicated by the arrow. The wipers 312, 313 and 314 and the commutator brushes 315, 316 and 317 carried by the rod 310 are elevated. The wipers 312 to 314 are arranged to make contact with the terminals of a bank 318 in which called lines, such as trunks leading to another selectively operable switching device, terminate, and the brushes 315 to 317 are arranged to engage the conducting and insulated portions of commutator segments 319, 320 and 321, respectively. Upon the energization of the relay 210, a circuit is closed from ground, through the front contact and armature of this relay, the lower contact of cam 220, the contact of key 207, the armature and back contact of the upper counting relay 1, the winding of the lower counting relay 1, to grounded battery. The lower counting relay becomes energized and closes a locking circuit for itself from ground, through the right-hand contact of sequence switch cam 222, the armature and front contact of the lower counting relay 1, and the windings of the upper and lower counting relays 1, to grounded battery. The upper counting relay 1 does not become energized, because of the shunt path closed to its winding from ground, through the front contact of the stepping relay 210. However, as soon as the commutator brush 316 engages the conducting portion of commutator segment 320, and connects ground through the left-hand contact of sequence switch cam 303 to the winding of relay 302, the stepping relay 210 is shunted out and by retracting its armature, permits the energization of the upper counting relay 1, which in turn extends

the counting relay circuit to the lower counting relay 0. When the commutator brush 316 engages the insulated portion of segment 320, the stepping relay 210 becomes again energized and causes in turn the completion of the circuit for the lower counting relay 0. When the commutator brush again engages the conducting portion of segment 320, the upper counting relay 0 becomes energized and closes a circuit for sequence switch 203 to drive it out of position 6 and into position 16. When the sequence switch moves out of position 6, the circuit including the lower winding of relay 230 is opened, and irrespective of the direction in which the current may traverse its upper winding, this relay cannot become energized. In position 16 of sequence switch 203 a circuit is closed from ground, through cam 263, conductor 264, lower contact of cam 107 and the power magnet of switch 108 to grounded battery, for moving this switch out of position 11 and into position 16. Lamp 152 is lighted. It is again noted that in practice a larger number of selective operations are performed than are disclosed in the present embodiment of the invention.

While these selective operations occur beyond the selector 300, the sequence switch 108 remains in position 11, because the sequence switch 203 is in some position between 6 and 16. These various selective operations are performed in positions 8, 10, 12 and 14 of sequence switch 203, the movement of this sequence switch from position 10 to position being controlled by the upper zero counting relay in the above described manner. When the last switch in the series (the connector switch) is set, the sequence switch 203 is moved into position 16 and causes in turn the movement of sequence switch 108 out of position 11 and into position 16.

When the sequence switch 108 moves out of position 11, it opens in the upper contact of cam 110 the locking circuit of relay 201. This relay becomes deenergized and closes a circuit through the left-hand contact of cam 202, for moving sequence switch 203 out of position 16 into position 1. The sender is now restored to normal and ready for use in the control of the establishment of another connection. The keys are restored to normal in the same manner as illustrated in the mentioned Patent No. 1,168,319.

The opening of the back contact of the upper counting relay 0 also results in the opening of the circuit including relays 210 and 302. Relay 210 becomes deenergized. Relay 302, however, is maintained energized through the path including the commutator brush 316 as long as this brush rests on the conducting portion of segment 302. As soon, however, as this brush engages the insulated portion of commutator 320, which indicates

that the wipers are properly centered on the proper set of terminals, the relay 302 becomes deenergized, and by opening the circuit of magnet 309, causes the arresting of the selector 300. The relay 302 also closes a circuit from ground, through its right-hand armature and back contact, upper left-hand contact of sequence switch cam 305, and the power magnet of sequence switch 306, to grounded battery, for moving the sequence switch out of position 2 and into position 5. A circuit is then closed from ground, through the sequence switch cam 322, the left-hand winding of a test relay 323, to grounded battery. This relay becomes energized and closes a circuit from ground, through its left-hand armature and front contact, the lower right-hand contact of sequence switch cam 324, and the power magnet of sequence switch 306, to grounded battery, for moving this sequence switch out of position 5 and into position 6. Upon energization, the relay 323 prepares a locking circuit for itself from grounded battery, through its right-hand winding, front contact and armature and the test wiper 312 of the selector 300. If the terminals on which the selector wipers are now resting are busy, then the test wiper 312 finds ground. For this reason, the relay 323 is maintained energized and closes a circuit from ground, through its left-hand armature and front contact, the upper contact of sequence switch cam 308, and the winding of magnet 309 to grounded battery. Under the control of magnet 309, the selector is caused to further travel in an upward direction until the test wiper 312 encounters the terminals of an idle trunk, that is to say, a terminal to which no ground is connected. Relay 323 becomes deenergized and connects ground through the contact of sequence switch cam 325, the right-hand back contact and armature of relay 323, and the test wiper 312 to the multiples of the test terminal engaged by the selector, whereby the terminals of this trunk will test busy at all selectors attempting to make connection therewith. The deenergization of relay 323 results also in the closure of a circuit from ground through the left-hand armature and back contact of relay 323, the upper right-hand contact of sequence switch cam 324 and the power magnet of sequence switch 306 to grounded battery, for moving this sequence switch out of position 6 and into position 16.

In practice the sequence switch 306 is not moved immediately from position 6 into position 16, but is stopped in intermediate positions for cooperating in the control of selectively operable switching devices employed in the extension of the desired connection beyond the selector 300. However, it is thought that the present invention will be clearly understood without describing

in detail these operations, and for this reason it is assumed that the connection is further extended to the called subscriber's station and that the called subscriber has been signaled and removed his receiver from the switchhook in answering the call. The circuit of a supervisory relay 326 is then closed in the well-known manner through the called substation, and this relay in turn closes the circuit of a relay 327. In position 14 of the sequence switch 306, a circuit was closed from grounded battery, through the left-hand winding of a relay 328, the outer back contact of relay 327, the lower right-hand contact of sequence switch cam 304, conductor 141, wiper 125, the lower contact of sequence switch cam 114, the secondary winding of a repeating coil 150, the winding of a polarized relay 151, the secondary winding of repeating coil 150, the upper contact of sequence switch cam 143, wiper 126, conductor 142, the upper right-hand contact of sequence switch cam 303, the primary winding of repeating coil 329, the inner back contact of relay 327, and the right-hand winding of relay 328, to ground. The relay 328 became energized and caused in turn the energization of a slow-acting relay 330. The polarized relay 151, however, did not become energized by current flowing through its winding in this direction. Upon the energization of the relay 327, the direction of the current flowing through the above-traced circuit is reversed, whereupon the polarized relay 151 becomes energized and causes the extinguishment of lamp 152, indicating to the operator that the connection has been completed.

When disconnection is desired the calling and called subscribers restore their receivers to the switchhooks, whereupon the supervisory relays 326 and 153 become deenergized. The relay 326 causes the deenergization of relay 327 which reestablishes the circuit including relays 328 and 151 to its original condition, whereby the polarized relay 151 becomes deenergized. Both lamps 152 and 154 are lighted now at the operator's position, indicating that disconnection is desired. The operator then removes plug 103 from jack 104, whereupon relay 106 becomes deenergized and closes a circuit from ground, through its armature and back contact, the right-hand contact of sequence switch cam 107, and the power magnet of sequence switch 108, to grounded battery, for moving this sequence switch out of position 16 and into position 18. A circuit is now closed from ground, through the right-hand contact of sequence switch cam 117, and the winding of a restoring magnet 155 to grounded battery. Magnet 155 becomes energized, and by attracting its armature, presses the brush rod 121 against a roller 156, constantly rotating in the direc-

tion indicated by the arrow. Under the control of this roller the brush rod 121 is caused to travel in a downward direction. When the brush rod is restored to its normal position, the commutator brush 128 is in engagement with the conducting segment 157, connecting ground through the upper right-hand contact of sequence switch cam 118, and the power magnet of sequence switch 108, to grounded battery. The sequence switch is then moved out of position 18 and into position 1, whereupon the magnet 155 becomes deenergized. When the sequence switch 108 is moved out of position 16 the ground is disconnected from the selector wiper 124, whereupon the relay 301 becomes deenergized and closes a circuit from ground, through its back contact and armature, the lower right-hand contact of sequence switch cam 305 and the power magnet of sequence switch 306, to grounded battery, for moving this sequence switch out of position 16 and into position 17. The movement of the sequence switch 108 out of position 16 results also in the deenergization of relay 328, which in turn causes the deenergization of relay 330. Upon the deenergization of relay 330 a circuit is closed from ground, through the armature and back contact of this relay, the lower left-hand contact of sequence switch cam 324 and the power magnet of sequence switch 306, to grounded battery, for moving this sequence switch out of position 17 and into position 18. A circuit is then closed from grounded battery, through the winding of a restoring magnet 330, and a sequence switch cam 331, to ground. The magnet 330 becomes energized, and by attracting its armature, presses the rod 310 against a roller 332, constantly rotating in the direction indicated by the arrow. Under the control of this roller, the brush rod is caused to travel in a downward direction, and when it is restored to its normal position, the commutator brush 317 engages a conducting segment 333, connecting ground through the upper left-hand contact of sequence switch cam 324 to the power magnet of sequence switch 306, for moving this sequence switch out of position 18 and into position 1. The magnet 330 is then deenergized. The switches are now restored to their normal position, and may be employed in the establishment of a new connection.

As above stated, due to the marginal adjustment of the relay 250, the closure of a circuit including its winding and a single resistance 251 does not result in the energization of this relay. Assuming that the operator instead of depressing key 206, depressed by mistake key 252 when desiring to establish the above described connection. The actuation of the key 252 results immediately in the adjustment of the sender

for controlling a certain operation, different from the one performed in response to the adjustment of the sender under the control of key 206. Or in other words, in response to the actuation of key 252, the counting 70 relays are adjusted to receive two impulses from the selector 122, causing the selector to engage the terminals of a different group of trunks from that engaged in response to the actuation of the key 206. The operator 75 then proceeds to actuate the other keys on her keyboard, but before depressing her start key 208, notices that she depressed the wrong key in the first row on her keyboard. In order to correct her error all she 80 will have to do is to depress the proper key, that is to say, key 206. Each row of keys is provided with a mechanical interlocking device, whereby the depression of a key causes the restoration of a key held in its actuated 85 position. For a short time, however, keys 252 and 206 are maintained simultaneously actuated, and for this reason two resistances 251 and 251^a are connected in parallel to the winding of marginal relay 250. The 90 marginal relay 250 becomes momentarily energized and closes a circuit from ground, through its front contact and armature, conductor 253, the lower contact of sequence switch cam 160, and the winding of a relay 95 161, to grounded battery. The relay 161 closes a locking circuit for itself from ground, through its right-hand armature and front contact, the upper contact of sequence switch cam 160, and the winding of relay 161, to grounded battery. The sequence switch 108 of the selector 122 is now 100 in some position between 2 and 7. The relay 161 closes a circuit from ground, through its left-hand contact and armature, the lower 105 contacts of sequence switch cam 162, and the power magnet of sequence switch 108, to grounded battery. Under the control of this circuit the sequence switch 108 is moved out of whatever position it may be in and into 110 position 8. The magnet 119 of the selector is deenergized and the magnet 155 energized by current flowing through a circuit extending from grounded battery, through the winding of magnet 155, the upper right-hand 115 and lower left-hand contact of sequence switch cam 162, and the left-hand armature and front contact of relay 161, to ground. Under the control of the magnet 155, the selector 122 is restored to normal in 120 the above described manner, and when it reaches its normal position, the brush 128 closes a circuit, through the conducting portion of segment 157, for moving the sequence switch 108 out of position 8 and into position 125 1. The magnet 155 and the relay 161 become deenergized. As soon as the sequence switch 108 reaches position 1, it is driven into position 2 by the circuit closed through the front contact of relay 106, and then the setting of 130

the selector 122 under the control of key 206, is accomplished in the above described manner.

It will be seen from the above that, due to the provision of the means including the resistances 251 and the relays 250 and 161, the operator may correct an error she made in selecting a key in one row, without the necessity of disturbing the properly selected 10 keys in the other rows. The invention may be applied to other rows of keys than the first row, to a plurality of rows of keys representing various digits, or to substation senders for full-automatic telephone exchange systems. The invention is disclosed in its present form, because it has been observed that semi-automatic operators make a relatively large number of mistakes in selecting the proper key in the first row which 20 designates the district or office in which the called line terminates.

If all the trunks belonging to the group selected by selector 300 are busy, then the established portion of the connection is released. This is accomplished in the following manner:

The commutator segment 319 is so arranged with respect to the segments 320 and 321, that if all the trunk lines in a selected group are busy, then after the last trunk line in the group has been tested, the commutator brush 315 is in engagement with the conducting portion of segment 319. The sequence switch 306 being in position 6 during the hunting operation of selector 300, a circuit is closed from ground, through commutator brush 315, the conducting portion of segment 319, the upper-right hand contact of cam 305, and the power magnet of 40 sequence switch 306 to grounded battery, whereupon this sequence switch is moved out of position 6 into position 17. The driving magnet 309 becomes deenergized.

After the termination of the group selecting operation, the sequence switch 203 moved into position 8. Therefore, when the sequence switch 306 reaches position 17, the relay 230 becomes energized, its upper winding being traversed by current flowing from 50 grounded battery, through the outer back contact of relay 327, the primary winding of repeating coil 329, the right-hand contact of cam 304, conductor 141, wiper 125, the upper contact of cam 144, conductor 211, the upper contact of cam 209, the upper winding of relay 230, the windings of stepping relay 210, the outer armature and back contact of the upper zero counting relay, conductor 115, the lower contact of cam 143, wiper 126, conductor 142, the upper right-hand contact of cam 303, the primary winding of repeating coil 329, the inner back contact of relay 327, and the right-hand winding of relay 325 to ground. The relay 230 closes a circuit 60 through its front contact and armature for

moving the sequence switch 108 out of position 11 and into position 16, whereupon the locking circuit of relay 201 is interrupted and the sequence switch 203 is moved into position 1.

In position 17 of sequence switch 306 an interrupter 340 is connected through the contact of sequence switch cam 341 to the relay 326, and causes this relay to intermittently energize and deenergize. Through the agency of relays 327 and 151 the relay 326 causes the flashing of lamp 152, which indicates to the operator that all the trunks are busy. She may then restore the connection in the above described manner.

What is claimed is:

1. In a telephone exchange system, a calling and a called line, means including a selectively operable switching device for interconnecting said lines, a variably adjustable controlling apparatus, means to adjust said apparatus to a setting in accordance with the designation of said called line, means dependent on the adjustment of said apparatus for variably operating said device, means to readjust a portion of the setting of said apparatus, and means operative thereupon to operate said device in accordance with said readjusted setting.

2. In a telephone exchange system, a calling and a called line, means including a selectively operable switching device for interconnecting said lines, a variably adjustable controlling apparatus, means responsive to each adjustment of said apparatus for variably operating said device, and restoring means for said device operated in response to any one of a plurality of adjustments of said apparatus.

3. In a telephone exchange system, a calling and a called line, a switching device, a variably adjustable controlling apparatus, means dependent on the adjustment of said apparatus for causing said device to interconnect said lines, means to readjust said controlling apparatus, restoring means for said device operable at will, and means incidental to the readjustment of said apparatus for operating said restoring means.

4. In a telephone exchange system, a calling and a called line, a switching device, means including a controlling apparatus for causing said device to perform a plurality of operations, a connecting circuit between said lines established upon the completion of all of said operations, restoring means for said device controlled by said apparatus, and means for rendering said last mentioned control effective only during certain operations of said device.

5. In a telephone exchange system, a calling and a called line, two selectively operable switching devices, a variably adjustable controlling apparatus, means responsive to the adjustment of said apparatus for success-

sively controlling said devices to interconnect said lines, a restoring means for one of said devices controlled by said apparatus, and means for rendering said last mentioned 5 control effective only prior to the operation of the other one of said devices.

6. In a telephone exchange system, a calling and a called line, a selectively operable switching device arranged to interconnect 10 said lines, a controlling apparatus for said device, restoring means for said device, means for adjusting said apparatus in accordance with the digits of the called number, means for changing the adjustment of said apparatus 15 with respect to one of the digits, and means operative thereupon for actuating said restoring means.

7. In a telephone exchange system, a calling and a called line, a selectively operable 20 switching device arranged to interconnect said lines, a sender for controlling said device, restoring means for said device, means including a plurality of actuating members for variably adjusting said sender, means 25 responsive to the operation of any one of said actuating members for controlling said switching device in accordance with the adjustment of said sender, and means responsive to the operation of more than one actuating member for operating said restoring 30 means.

8. In a telephone exchange system, a calling and a called line, a selectively operable 35 switching device arranged to interconnect said lines, a sender for controlling said device, restoring means for said device, means including a plurality of actuating members for variably adjusting said sender, means 40 responsive to the operation of any one of said actuating members for controlling said switching device in accordance with the adjustment of said sender, and means responsive to the simultaneous operation of a plurality of members for operating said restoring 45 means.

9. In a telephone exchange system, a calling and a called line, means including a selectively operable switching device for interconnecting said lines, a variably adjustable 50 controlling apparatus, means operative in response to a certain adjustment of said apparatus for causing said device to perform a certain operation, restoring means for said device operable in response to certain other adjustment of said apparatus, and means operative upon restoration of said device for causing it to perform a certain other operation in accordance with said certain other adjustment of said apparatus. 55

10. In a telephone exchange system, a calling and a called line, means including a selectively operable switching device for interconnecting said lines, a variably adjustable 60 controlling apparatus for said device, restoring means for said device, a relay for

controlling said restoring means, and a circuit for said relay controlled by said apparatus.

11. In a telephone exchange system, a calling and a called line, means including a selectively operable switching device for interconnecting said lines, a variably operable 70 controlling apparatus comprising a plurality of switches, means responsive to the actuation of each switch for controlling the operation of said device, restoring means for said device, a marginal relay for controlling said restoring means, a circuit for said relay having a resistance in each of said branches, and means controlled by each of said 75 switches for closing a branch.

12. In a telephone exchange system, a calling and a called line, means including a selectively operable switching device for interconnecting said lines, an operator's controlling apparatus comprising a plurality of keys, means responsive to the actuation of each key for selectively controlling the operation of said device, restoring means for said device, and means responsive to the actuation of a key for operating said restoring 85 means.

13. In a telephone exchange system, a calling and a called line, means including a selectively operable switching device for interconnecting said lines, an operator's controlling apparatus comprising a plurality of keys, means responsive to the actuation of each key for selectively controlling the operation of said device, restoring means for 95 said device, and means responsive to the simultaneous actuation of a plurality of 100 keys for operating said restoring means.

14. In a telephone exchange system, a calling and a called line, means including a selectively operable switching device for interconnecting said lines, an operator's controlling apparatus comprising a plurality of keys, means responsive to the actuation of each key for variably controlling the operation of said device, restoring means for said device, a relay for controlling said restoring means, and means controlled by said keys for operating said relay. 110

15. In a telephone exchange system, a calling and a called line, two switching devices, a controlling apparatus, means controlled by said apparatus for successively operating said devices to interconnect said lines, means for rendering busy said called line, a restoring means for each of said devices, means for actuating the restoring means of each device if the called line is busy, and means controlled by said apparatus for controlling the restoring means of one of said devices. 115 120 125

In witness whereof, I hereunto subscribe my name this 31st day of August, A. D., 1918.

ALBEN E. LUNDELL.
